UNITED STATES PATENT OFFICE.

JAMES CAVANAGH, JR., OF BOSTON, MASSACHUSETTS, ASSIGNOR TO UNITED SHOE MACHINERY COMPANY, OF PATERSON, NEW JERSEY, A CORPORATION OF NEW JERSEY.

INSOLE.

1,113,540.

Specification of Letters Patent.

Patented Oct. 13, 1914.

Application filed March 28, 1907. Serial No. 365,142.

To all whom it may concern:

Be it known that I, JAMES CAVANAGH, Jr., citizen of the United States, residing at Boston, in the county of Suffolk and State 5 of Massachusetts, have invented certain new and useful Improvements in Insoles; and I do hereby declare the following to be a full, clear, and exact description of the invention, such as will enable others skilled in 10 the art to which it appertains to make and use the same.

In preparing an insole for the operation of an inseam shoe sewing machine, a stitch-receiving rib is formed on one surface of 15 the sole near the margin from a point on one side of the sole near the heel end to an opposite point on the opposite side of the sole. This rib is formed by the action of knives which either split the edge of the sole 20 to form a lip which is subsequently turned up at substantially right angles to the surface of the sole, or which split the edge of the sole and form a channel and channel flap, or which form a channel or channel 25 flap and cut away a portion of the edge of a sole to form a shoulder.

On account of the difficulty and practical impossibility of entering and removing the knives at the points where the stitch-receiving 30 rib should begin and end, the knives are entered into and removed from the sole at points on the edge of the heel portion of the sole and as a result the heel portion of the sole is weakened so that it is liable to 35 become more or less distorted during the subsequent operations of lasting and heelng the shoe. Also when the edge of the insole is split and a portion thereof turned up to form a lip, it is necessary to cut the lip at 40 the point where the inseam is to begin and end in order to permit the portion of the lip at the heel end of the sole to be pressed down flat, this cutting operation being performed either before or during the lasting 45 operation.

The object of the present invention is to produce an insole in which the stitch-receiving rib begins and ends at the desired points and in which the heel portion of the 50 sole is not cut or injured. With this object in view, the present invention contemplates cutting transverse slits in the insole at the points where it is desired to have the stitch-

receiving rib begin and end, and in utilizing these slits to enter and remove the rib-forming knife or knives so that the rib formed by the knives begins at one slit and ends at the other, and the heel portion of the sole is not cut or injured by the knife or knives. The slits may extend into the 60 sole at right angles to the surface thereof, but preferably extend obliquely toward the toe end of the sole as thereby no abrupt angle is formed at the junction of the heel and shank portions of the sole, and a better 65 surface is provided to receive the crimped-in edge of the counter when the shoe is lasted.

The present invention will be clearly understood from an inspection of the accompanying drawing, in which—

Figure 1 is a plan view of an insole provided with transverse slits to mark the beginning and end of the stitch-receiving lip; Fig. 2 is a view in side elevation of the insole illustrated in Fig. 1, showing the preferred oblique arrangement of the slits; and Fig. 3 is a plan view of the sole after the sole has been acted upon by the edge splitting and channeling knives of a channeling machine, and after a portion of the edge of 80 the sole has been turned up to form a lip.

As illustrated in the drawing, the insole 1 is first provided with two slits 2 and 3 which extend transversely of the sole from each edge toward the medial line and which 85 are located at the points at which the stitch-receiving lip is to begin and end. These slits may be made by means of a hand knife or by any suitable machine adapted to the purpose. The slits preferably extend obliquely 90 to the surface of the sole toward the toe end as indicated in Fig. 2.

The insole provided with slits, as indicated in Figs. 1 and 2, constitutes a complete article which is produced before the sole is 95 subjected to the action of the knife or knives of a machine for forming the stitch-receiving rib. The stitch-receiving rib may be formed by subjecting the insole to the action of any suitable insole channeling, edge-splitting, or edge-shouldering machine. When the insole is presented to such a machine the slits 2 and 3 provide respectively an entrance and an exit for the rib-forming 100 knife or knives so that the stitch-receiving 105 rib begins at the slit 2 and ends at the slit 3.

In Fig. 3 a channel flap is indicated at 4, and an upturned lip is indicated at 5, the channel flap having been formed by the channeling knife of a channeling and edge splitting machine, and the lip having been formed by the splitting knife of such machine and subsequently turned up at substantially right angles to the surface of the sole. In this sole it will be seen that the heel portion of the sole is not cut or injured but is in its original flat condition, and that when the shoe is lasted no cutting operation need be performed upon the upturned lip 5. It will also be seen that the stitch-receiving rib 15 begins and ends at precisely the desired points so that the counter can be readily lasted over the heel seat and secured in the proper position. By providing the insole with slits before the stitch-receiving rib is 20 formed, the points at which the rib begins and ends are determined with accuracy and uniform results upon a large number of soles can be secured.

The nature and scope of the present invention having been indicated, and the manner in which the invention is to be practised 25

having been specifically described, what is claimed is:—

1. An insole provided with transverse slits extending part way only through the thickness of the insole, said slits marking the beginning and the end of the stitch receiving rib, said insole being provided with a stitch receiving rib extending around the edge of the sole from one of said slits to the other 35 and the edge of the heel being intact or solid.

2. An insole blank provided with transverse slits extending obliquely to the surface of the sole toward the toe end of the 40 sole and part way only through the thickness of the sole arranged to mark the beginning and end of the stitch-receiving rib, said insole being provided with a stitching rib and having the edge of its heel portion 45 intact or solid.

In testimony whereof I affix my signature, in presence of two witnesses.

JAMES CAVANAGH, Jr.
